UNITED STATES PATENT OFFICE.

GEORGE C. KNAUFF, OF CHICAGO, ILLINOIS.

SWITCHING SOCKET OR CONNECTOR.

1,136,681.

Specification of Letters Patent. Patented Apr. 20, 1915.

Application filed December 12, 1913. Serial No. 806,239.

To all whom it may concern:

Be it known that I, GEORGE C. KNAUFF, citizen of the United States, residing at Chicago, in the county of Cook and State 5 of Illinois, have invented certain new and useful Improvements in Switching Sockets or Connectors; and I do hereby declare the following to be a full, clear, and exact description of the invention, such as will enable others skilled in the art to which it 10 appertains to make and use the same.

My invention relates to sockets or connectors and more particularly to a plug and socket combination suitable for use with 15 automobile lighting circuits. It has been customary heretofore to equip sockets and plugs of this kind with circuit terminals contacting continuously with each other when the plug is coupled to the casing, there- 20 by permitting the circuit to be opened only by detaching the plug from the casing.

The prime object of my invention is to provide a simple, compact and effective construction which will permit the circuit to 25 be opened without detaching the plug (or one of the terminal-carrying elements) from the casing by merely rotating one of the terminal-carrying elements with respect to the other or with respect to the casing.

30 Other objects are to provide a construction in which a single spring will coact with the contacting parts to insure a good electrical connection when the plug is in the position in which it closes the circuit, and by 35 which the same spring will coact with another portion of the plug when the latter is in the circuit-opening position, to maintain the plug and socket securely coupled.

Other objects will appear from the accompanying drawings, in which—

Figure 1 is a longitudinal section of a lamp socket and plug embodying my invention. Figs. 2 and 3 are transverse sections through Fig. 1 along the lines 2—2 45 and 3—3 respectively. Fig. 4 is a fragmentary elevation of the right hand end portion of Fig. 1. Fig. 5 is a longitudinal section through an alternative embodiment of my invention. Fig. 6 is a transverse section through Fig. 5 along the line 6—6.

50 My invention is equally applicable to lamp sockets or wire connectors equipped with movable plugs, and may be embodied in a number of different forms possessing substantially equal advantages, as will be dis-

closed hereafter. Fig. 1 shows my invention as applied to a lamp socket having a casing 1 equipped at one end with bayonet slots 2 adapted to receive and engage lateral projections 3 upon the base of a lamp 4 to 60 couple the said lamp to the casing. Mounted within the casing is an insulating cylinder 5, carrying axially thereof a metal cylinder 6 equipped with a plunger 7 projecting from the forward end thereof, the tip of 65 said plunger contacting with the axially disposed terminal 8 of the lamp 4. The cylinder 5 is preferably rigidly secured within the casing 1 by a suitable means such as a pin 9. Housed within the cylinder 6 70 and bearing at its respective ends against the slotted head 10 of the said cylinder and against the plunger 7 is a compression spring 11, which spring continually presses the said plunger forwardly of the cylinder 75 and thereby forces the plunger into contact with the terminal 8 of the lamp. The rear end 10 of the cylinder 6 is equipped with a head 12 extending radially of the casing, the said radial extension having a perforation 80 slidingly fitting the stem 13 of a plunger equipped with a head 14 sliding within a bore in the insulating body 5, the said bore being disposed longitudinally of the said body and radially outward of the cylinder 85 6. The rear end of the casing 1 is equipped with bayonet slots adapted to receive and interlock projections 15 upon a plug 16, each of said slots being equipped with a pair of 90 socket portions 17 separated from each other at a considerable distance circumferentially of the casing and connected by a slot portion 18 extending circumferentially of the casing. It will be evident from Fig. 4 that the said circumferential slot portion will 95 permit the projection 15 to be interlocked with either of the sockets 17 by partially rotating the plug 16 with respect to the casing, so that the said plug may readily be coupled to the casing in either one of two 100 rotationally separated positions. Mounted within the plug 16 is the terminal 19 of a wire 20 forming one terminus of a circuit, the said terminal 19 being connected at its forward end to a substantially rectangular plate 21 disposed transversely of the casing 1 upon the forward surface of the plug 16, the said plate 21 being preferably kept from 105 rotating with respect to the said plug by having prongs 22 bent from the plate and 110

forcibly indented into the rubber or other material of which the plug 16 is made. The plate 21 is so disposed with reference to the bayonet slots at the adjacent end of the 5 casing and with reference to the plunger 14 that the said plunger will bear against one end of the said plate, as shown in Fig. 1, when the plug 16 is coupled to the casing with the projection 15 in one of the said 10 socket portions of the bayonet catch formations at that end of the socket. Upon rotating the plug to bring the projection 15 into interlocking relation with the other socket 17, the tip of the plunger 14 will be 15 brought out of engagement with the plate 21, so that this tip will bear against the insulating body of the plunger 16, thereby opening the circuit. To insure a good electrical contact between the plunger and the 20 plate 21 when the plug is in one of its said interlocked positions, and to insure a forcible interlocking of the plug and the casing when the plug is in either of its said coupled positions, I preferably provide a spring 23 25 in the perforation housing the plunger 14, which spring will continually press the said plunger 14 rearwardly into engagement with either the plate 21 or the exposed forward surface portion of the plug 16. The circuit 30 to the axial terminal of the lamp will then be completed from the wire 20 through the terminal 19, contact plate 21, plunger 13, radial plate 12, cylinder 10 and plunger 7; current being carried to the other terminal 35 of the lamp by the contact of the shell 35 of the lamp base with the casing 1 of the socket, to which casing one terminal of the circuit is grounded as indicated in dotted lines in Fig. 1.

40 Instead of positioning the plungers 7 and 14 in two separate cylinders each housing a compression spring and having their tips out of alignment longitudinally of the socket, I can produce the same effect by 45 mounting both plungers in a single cylinder positioned at an angle to the axis of the socket and interposing a single spring between the two plungers, as in Fig. 5. In so doing, the terminal or conducting member 50 contacting with the tip of the plunger mounted in the other insulating member may be radially enlarged as in Fig. 5. Thus, Fig. 5 shows a separable wire connector having a wire-terminal 24 mounted axially 55 of an insulating body 25, the said body being concaved at its rear surface. Bearing against the said rear surface and threaded to the rear end of the terminal 24 is a curved contact plate 26 equipped with beveled edge 60 portions 27 for enabling the adjacent tip of the plungers 28 to ride up on the face of the said contact plate. In the embodiment of Fig. 5, the plunger 28 is mounted in a terminal 29 disposed at an angle to the axis of 65 the insulating plug 30 housing the said ter-

minal, thereby enabling this type of construction to be effected with a relatively small diameter of plug and casing.

While I have shown and described the casing of my socket or connector as equipped with slot formations including entrance portions 38 permitting the separation of the rotatable plug from the casing of the socket or connector, I do not wish to be limited to such a provision. The entrance portion 75 might be omitted as shown by dotted lines in Fig. 4 thereby connecting the plug permanently to the structure while still permitting of its operation as a switching means for opening and closing the circuit. Neither 80 do I wish to be limited to other details of the construction herein disclosed, such as the pictured type of the formations upon one of the terminal-carrying members which coact with formations upon another portion 85 of the socket to lock the circuit terminals against relative rotation, as such details might be varied in many ways without departing from the spirit of my invention.

I claim as my invention:

1. In a socket and plug combination, a plug, a circuit terminal carried thereby and projecting beyond the forward end of the plug; a casing equipped with means for coupling the plug thereto in either of two 95 rotationally separated positions, the said coupling means permitting the plug to be rotated relatively to the casing to move the plug from one to the other of its said positions; and a second circuit terminal mounted 100 within and insulated from the casing forwardly of the said plug; one of the said terminals equipped with an extension substantially radial of the casing, the other thereof presenting a tip disposed at one side 105 of the axis of the casing and contacting with the said radial extension upon the other terminal when the plug and casing are in one of their said coupled positions, the said disposition of the contacting portions of the 110 said terminals causing the same to be brought out of contacting relation when the plug is rotated to the other of its said coupled positions.

2. In a socket and plug combination, a 115 plug, a circuit terminal carried thereby and projecting beyond the forward end of the plug; a casing equipped with means for coupling the plug thereto in either of two 120 rotationally separated positions, the said coupling means permitting the plug to be rotated relatively to the casing to move the plug from one to the other of its said positions; and a second circuit terminal mounted 125 within and insulated from the casing forwardly of the said plug; one of the said terminals equipped with an extension substantially radial of the casing, the other thereof presenting a tip disposed at one side 130 of the axis of the casing and contacting with

the said radial extension upon the other terminal when the plug and casing are in one of their said coupled positions, the said disposition of the contacting portions of the 5 said terminals causing the same to be brought out of contacting relation when the plug is rotated to the other of its said coupled positions; and spring means associated with one of the said terminals and 10 coöperating with the said formations to hold the plug in either of its said coupled positions.

3. In a socket and plug combination, a 15 plug, a circuit terminal carried thereby and projecting beyond the forward end of the plug; a casing equipped with means for coupling the plug thereto in either of two rotationally separated positions, the said coupling means permitting the plug to be 20 rotated relatively to the casing to move the plug from one to the other of its said positions; and a second circuit terminal mounted within and insulated from the casing substantially axially thereof and forwardly of 25 the said plug, the rear end thereof equipped with an extension substantially radial of the casing; the first named circuit terminal being disposed at an angle to the common axis of the plug and the casing, the forward 30 end of the said terminal contacting with the said extension upon the other terminal when the plug is in one of its said coupled positions; the said angular disposition of the first named terminal causing the forward 35 end thereof to be moved out of contact with the rear end of the other terminal upon rotation of the plug to the other of its coupled positions, thereby opening the circuit.

4. In a socket and plug combination, a 40 plug, a circuit terminal carried thereby and projecting beyond the forward end of the plug; a casing equipped with means for coupling the plug thereto in either of two rotationally separated positions, the said 45 coupling means permitting the plug to be rotated relatively to the casing to move the plug from one to the other of its said positions; a second circuit terminal mounted within and insulated from the casing sub- 50 stantially axially thereof and forwardly of the said plug, the rear end thereof equipped with an extension substantially radial of the casing; the first named circuit terminal being disposed at an angle to the common 55 axis of the plug and the casing, the forward end of the said terminal contacting with the said extension upon the other terminal when the plug is in one of its said coupled positions; the said angular disposition of the 60 first named terminal causing the forward end thereof to be moved out of contact with the rear end of the other terminal upon ro-

tation of the plug to the other of its coupled positions, thereby opening the circuit; and spring means associated with one of the said 65 terminals and pressing the said ends of the terminals into forcible impingement when the plug is in the first of its said coupled positions.

5. In a socket and plug combination, a 70 plug, a circuit terminal carried thereby and projecting beyond the forward end of the plug; a casing equipped with means for coupling the plug thereto in either of two rotationally separated positions, the said 75 coupling means permitting the plug to be rotated relatively to the casing to move the plug from one to the other of its said positions; and a second circuit terminal mounted within and insulated from the casing for- 80 wardly of the said plug; the adjacent ends of the said terminals contacting with each other when the plug is in one of its said coupled positions, one of the said terminals being disposed at an angle with the common 85 axis of the casing and plug, the said angular disposition of the last named terminal caus- 90 ing the said adjacent ends of the terminals to be brought out of contact with each other when the plug is moved to the other of its said coupled positions.

6. In a socket and plug combination, a 95 plug, a circuit terminal carried thereby and projecting beyond the forward end of the plug; a casing equipped with means for coupling the plug thereto in either of two rotationally separated positions, the said 100 coupling means permitting the plug to be rotated relatively to the casing to move the plug from one to the other of its said positions; a second circuit terminal mounted within and insulated from the casing for- 105 wardly of the said plug; the adjacent ends of the said terminals contacting with each other when the plug is in one of its said coupled positions, one of the said terminals being disposed at an angle with the common axis of the casing and plug, the said angular disposition of the last named terminal caus- 110 ing the said adjacent ends of the terminals to be brought out of contact with each other when the plug is moved to the other of its said coupled positions; and spring means 115 associated with one of the said terminals and pressing the said adjacent ends thereof into forcible impingement when the said ends are in their said relatively contacting position.

In testimony whereof I have signed my name in presence of two subscribing witnesses.

GEORGE C. KNAUFF.
